UNITED STATES PATENT OFFICE.

MARY E. PIKE, OF NEW ROCHELLE, NEW YORK.

GARMENT-HANGER.

SPECIFICATION forming part of Letters Patent No. 736,150, dated August 11, 1903.

Application filed November 12, 1902. Serial No. 131,034. (No model.)

To all whom it may concern:

Be it known that I, MARY E. PIKE, a citizen of the United States, and a resident of New Rochelle, in the county of Westchester and State of New York, have invented a new and Improved Garment-Hanger, of which the following is a full, clear, and exact description.

The purpose of my invention is to provide a garment-hanger especially adapted for hanging skirts and to so construct the device that it will be simple, durable, and economic and adjustable lengthwise, whereby to accommodate itself to any size of waistband, and to provide a supporting device which will enable a number of skirts carried by such hangers to be hung in a closet in a small space.

A further purpose of the invention is to provide a skirt-hanger in which the suspension member is adjustable upon the body member, enabling a skirt to be perfectly balanced and to be hung straight no matter how much heavier one portion of the skirt may be than the other.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved device and a skirt suspended therefrom. Fig. 2 is a bottom plan view of the device. Fig. 3 is a transverse section taken practically on the lines 3 3 of Figs. 2 and 4, and Fig. 4 is a longitudinal section taken substantially on the line 4 4 of Fig. 3.

The body of the device is made in two sections arranged to slide one within the other, whereby the body may be lengthened and shortened to accommodate the hanger to different waist-measurements of skirts. In detail one section of the body consists of two rods 10 and 11, terminating at their outer ends in a downwardly-curved hook 12, being secured at their opposite or inner ends to a guide-loop 13. The other section of the body consists also of two rods 14 and 15, which lie and are adapted to slide between the rods 10 and 11, said rods 14 and 15 terminating at their outer ends in a downwardly-curved hook

12^a and are secured to a guide-loop 16 at their inner ends. The guide-loop 16 slides upon the rods 10 and 11, while the opposing guide-loop 13 slides upon the rods 14 and 15. It will thus be observed that the body of the device is telescopic and may be readily contracted or lengthened at will.

Women's skirts are frequently heavier at the back than at the front or the front may be heavier than the back or one side may be heavier than the other. Under such conditions when a hanger is used having the supporting hook or shank fixed to the central portion of the hanger the skirt carried by the hanger is unequally supported, and it will naturally sag where the preponderance of weight exists. In order to overcome this difficulty and to hold the skirt horizontally straight at the band under all conditions, I provide an equalizing-sleeve 17, adapted to slide upon the body of the device between the guide-loops 13 and 16. This equalizing-sleeve is provided, preferably at its center, with opposing downwardly-extending side ears 18, together with a slot 19 between said ears, and in said ears the ends of a rod 19^a are supported. A cam-knuckle 20 is mounted to turn with the rod 19^a, having such relation to the under face of the body of the device that when the elevated surface of the cam-knuckle is brought uppermost it will extend through the slot 19 and jam against the body and hold the equalizing-sleeve in adjusted position, as in use the said equalizing-sleeve may need to be locked centrally on the body or at a point at one or the other side of the center of said body, as may be required to balance the skirt and hold its band in a true horizontal position, as is shown in Fig. 1. When the depressed surface of the cam-knuckle 20 is opposite the slot 19, the equalizing-sleeve 17 is free to slide on the body, and the said cam-knuckle is preferably operated by an attached or integral finger-piece 21. It is obvious that the locking device above described serves the dual purpose of locking the equalizing-sleeve to the body and locking the sliding sections of the body in the position to which they may have been adjusted.

The equalizing-sleeve 17 is provided with an upwardly-extending centrally-located

shank 22, terminating at its outer end in a hook 23, which is preferably made to engage with a metallic traveler 24 in the form of a staple, said traveler being secured to the under face of a shelf 25 of a closet, for example, whereby a number of skirts may be supported from the said traveler or elongated staple; but the garment-hanger may be suspended from an overhead or a side-supported hook of any marketable type, if desired.

In placing the skirt A upon the hanger the ends of the waistband are connected and the band is laterally stretched and opposing fabric loops or metal eyes secured to the band are received by the hook terminations 12 and 12^a of the body.

I desire it to be understood that the body of the hanger may be made in one section of single or double construction and that the equalizing-sleeve may be made to slide from end to end of the said single section. Under this construction the same balancing result will be obtained, but the body will not be adjustable as to length. I furthermore desire it to be understood that instead of the lever locking device illustrated a set-screw or its equivalent may be employed and that when the body is made in adjustable sections it may be telescopic.

Having thus described my invention, I claim as new and desire to secure by Letters Patent—

1. A garment-hanger having a body constructed in slidably-connected sections, each section comprising a loop having parallel sides closed at one end and open at the other, one side of one of the loops being received between the two sides of the other loop, all the sides of said loops being disposed in a horizontal plane, the outer or closed ends of said loop-sections being bent downwardly substantially at right angles to the main portion of said section and formed into hooks at their extreme ends, an equalizing-sleeve mounted to slide upon the body, provided with an open-

ing in one face, and a suspension member, and a locking device carried by the equalizing-sleeve, arranged to operate through the opening therein upon said body to clamp the sections of the loop between the sides of said body without imparting any lateral strain upon said sections, for the purpose specified.

2. A garment-hanger having a body constructed in slidably-connected sections each bent into a hook at its outer end, an equalizing-sleeve mounted to slide upon the body, provided with an opening in one face, and a suspension member, and a locking device carried by the equalizing-sleeve, arranged to operate through the opening therein upon said body, for the purpose specified.

3. A garment-hanger having a body constructed in slidably-connected sections, each section comprising a loop having parallel sides closed at one end and open at the other, one side of each one of the loops being received between the sides of the other loop, the outer or closed portions of said loops being formed into hooks at their extreme ends, the open ends of said loops being each secured together by a transverse guide-loop through which the two sections of the coöperating loop pass, an equalizing-sleeve mounted to slide upon the body, having an opening in its under face, a suspension member centrally attached to the upper face of the said sleeve, a cam-knuckle pivoted upon the equalizing-sleeve at the opening therein to clamp the sections of the loops between the sides of said body without imparting lateral strain upon said parallel sections, and a finger-piece for the cam-knuckle, substantially as described.

In testimony whereof I have signed my name to this specification in the presence of two subscribing witnesses.

MARY E. PIKE.
